By his Attorney

Augustus M. Henry

UNITED STATES PATENT OFFICE

ISADORE LAWRENCE LESAVOY, OF NEW YORK, N. Y.

PLAYING CARDS

Application filed January 4, 1929. Serial No. 330,336.

The present invention, at least indirectly, relates to the well-known game of chess; but, at the same time, the subject of the invention is a new deck of playing cards.

5 The invention has two main objects: the first, to provide a novel and recreational game; and, second, to provide a playing card game of preparatory instructional value to those intending later on to take up for the 10 first time the playing of the ordinary game of chess, or even to those who have previously attempted to play the ordinary game of chess but without marked success due to a failure to realize certain relative sacrifice- 15 values of the different chessmen according to the principles set forth in United States Letters Patent to me No. 1,628,412.

The present invention, and various other 20 objects and advantages thereof, will be clearly understood from the following description of an embodiment thereof as at present preferred, and illustrated in the accompanying drawing; it being understood, of course, that such embodiment presents 25 merely an illustrative one of the many possible ways of carrying out the invention.

Therefore, as to the form of the invention shown in said drawing, it is particularly to be understood that the detailed description 30 thereof now to be given is not to be taken at all as defining or limiting the invention itself. It is desirable also to emphasize at this point that, broadly, the essence of the invention is the provision of a plurality of 35

playing cards of different obverse or face markings, such markings significant of different chessmen and/or different numbers or values relative to trick-taking power or honor-worth. Where such numbers or values 40

are in any suitable way marked upon or indicated by the cards, they are preferably carried by the faces of the cards in such wise that a card representative of a particular kind of chessman, at least in the case of the 45

cards representative of the attacking chessmen (i. e., all chessmen except the King), will also carry a number or value more or less appropriate to the attacking or relative-sacrifice-value of the chessman indicated by 50 the card, in an actual game of chess. The

fundamentals of the invention are as already stated; whether or not all chessmen are given representative cards; likewise whether or not a card or cards additional to the chessmen-representative cards are incorporated; further, whether or not cards are employed to make up the new deck to have more or less cards in toto, or more or less cards of a particular "suit" or color, or more or less cards representative of a particular type of chessman, than as hereinafter described; further, whether or not some or all of the cards of the new deck vary from those shown in the accompanying drawing, particularly as to the pictorial and numerical representations shown thereon, by substitution or elimination or addition; also, whether or not the new deck of cards be intended to be played by the number of players or according to the rules of the particular game hereinbelow set forth in detail as a means of facilitating a description of the embodiment of the invention illustrated in said drawing.

As to the particular game just referred to, then, the rules for the playing of the same given in detail hereinbelow are not, of course, to be taken as at all defining or limiting the invention itself, any more than the particular cards and the particular deck of cards hereinbelow likewise described in detail. While said particular game is one well calculated firmly to fix in the memory of a player certain fundamental facts and factors important to be kept in mind in successfully playing the ordinary game of chess, and while said particular game has been found to be continuously interesting over prolonged playing periods; it is obvious that a multitude of other and different games according to other rules now or hereafter to be devised may be played with the illustrated and other card and deck embodiments of the invention, designed for various numbers of players, just as are the long-known cassino deck of 52 cards, pinochle deck of 48 cards, bezique deck of 32 cards and Spanish deck of 40 cards each capable of use in playing many games.

To sum up all the foregoing, the scope of protection contemplated is to be taken solely from the appended claims, interpreted as

broadly as is consistent with the prior art, and with explanatory references to the specification only where a claim is ambiguous or to be impliedly limited beyond its express terms to avoid such art in order to save the validity of the claim.

In the accompanying drawing,

Figs. 1 to 6 show the obverse sides or faces of different cards each representative of a different kind of chessman, marked to suggest such chessman and appropriate numerical values in accordance with present preferences, while

Fig. 7 similarly illustrates an auxiliary card having markings not necessarily suggestive of a chessman or the game of chess, which may also form a part of the new deck.

In the embodiment of the invention as now preferred, the deck consists of 33 cards, of two suits or colors, say "red" and "black"; the deck consisting of 16 cards of each suit, to wit, one King (Fig. 1), one Queen (Fig. 2), two Castles (Fig. 3), two Knights (Fig. 4), two Bishops (Fig. 5), and eight Pawns (Fig. 6); and also an extra card, as a Joker (Fig. 7). Such a deck provides, for instance, a three-handed game, or a four-handed game wherein the players take turns in acting as dummy according to any rule or rules formulated; providing say eleven cards for each of the three players on each deal, and consequently providing for eleven tricks for each game; while for a two-handed game the deck just-described could be furnished with the auxiliary card of Fig. 7, or the two players could leave the latter card out of play; thus providing say 16 cards for each of the two players on each deal, and consequently providing for 16 tricks for each game.

Each of the various cards making up any desired deck according to the present invention is preferably of course so made up that the reverse or back thereof is either plain or of the same design as all the other cards, so as to be non-indicative of the markings on the obverse sides or faces of the cards.

Also, for convenience, as in the case of ordinary playing cards, each of the cards of the deck illustrated in the drawing has an obverse which is of the reversed-indicia type. Consequently, herein, for shortening the descriptive matter, reference will now only be made to the upper half of each of the cards illustrated in said drawing.

As will be noted, each card as shown in Figs. 1 to 6, may carry a horizontal line or lines midway between its top and bottom, to mark the zone of indicia-reversal; and above the left-hand end of this line, there is inscribed a number (the same numeral as is carried at the upper right-hand corner of the card); so that at least one of the numerical indications just referred to, on each of a plurality of cards, will always be visi-

ble to a player having said plurality of cards spread fanwise in his hand.

Referring further to each of the cards shown in Figs. 1 to 6, the upper left-hand corner carries the name or initial (as "King", Fig. 1, or "B", Fig. 5) of the chessman which the card represents; the upper right-hand corner carries a numeral indicative of the relative sacrifice-value of that chessman (as "8", Fig. 2, or "1", Fig. 6); the cards designated at their upper left-hand corners by only the initial of the chessman represented carry elsewhere thereon the full name for which that initial stands (as "Knight", Fig. 4, and "Pawn", Fig. 6); a card representant of a chessman known to players of different schools under different names carries thereon the additional name in parentheses (as "Officer", Fig. 5); cards appropriate to chessmen representing relatively archaic elements of warfare carry a more up-to-date synonym in parenthesis (as "Fort", Fig. 3, "High Officer", Fig. 4, or "Soldier", Fig. 6); and each card carries, as its main and outstanding indicium, a picture of the chessman represented thereby, not only as to most usual shape, but also as to relative height so far as other chessmen shown on other cards are concerned.

(Although not so illustrated, the word "Rook" may also be inscribed on the face of the card of Fig. 3, if desired; since the chessman there represented is sometimes also referred to by chess-players as a Rook.)

The King and Queen cards (Figs. 1 and 2) may carry, as illustrated, in order further to carry on the work of chess-teaching to players of the new card game, miniature representations of the dissimilar crowns commonly employed to designate King and Queen pieces in pocket chess-sets and in diagrams of play in chess text-books. Conveniently, as shown in the drawing, these crowns may also be placed at the upper left-hand corners of the cards.

The Knight (Fig. 4) and the Bishop (Fig. 5) are sometimes, perhaps ordinarily, deemed to have the same maneuverability-factor, or attacking efficiency, that is, to have the same sacrifice-value; however, my own observations have persuaded me that the Knight is generally of somewhat slightly higher sacrifice-value than the Bishop, and consequently, and because it is desirable in a card game not to have two cards of distinctly different designs have the same trick or honor value, the numerical indications on the Knight, it will be noted, are "2+", while those on the Bishop are "2".

Where the new deck includes a plurality of suits of chessman-indicative cards, as in the embodiment being described, these suits, as already indicated, may conveniently be established by the use of different colors, applied in any desired way, or to any desired spot or spots, on the faces of the cards.

For instance, the two suits, say red and black, already referred to in connection with the 32 or 33-card deck pursuant to the present invention now being described, may be indicated, respectively, by printing all the indicia on the faces of the cards as shown in Figs. 1 to 6, in red ink, or in black.

Let us say that the game desired to be played with the embodiment of the invention including cards as above described, is to be a three-handed one, that honors as well as tricks are to be counted, and that such game is to be the particular one hereinabove referred to as having been actually played with continuous interest over a prolonged period.

Hoyle's general rules for card games are followed in all particulars except those now to be mentioned. The game may be an auction or bidding one, or not, as desired. The dealer deals the cards one by one, to each of the three players, for two deals, then deals three cards to the table for a widow or blind, then continues dealing to the three players one card at a time, until each of the three players holds ten cards. The pone, or the player to the left of the dealer, first chooses one of the three face-down cards in the blind, and adds it to his cards received on the deal, to give him a hand of eleven cards. The next player to the left does the same, and finally the dealer takes the remaining card in the blind and adds it to his own hand. The pone now leads, and the other players, in the order just indicated, follow.

If it is a non-bidding game, the pone may, before the playing of the first trick, declare trumps; that is, designate the red or the black suit as trumps for that particular game. If it is a bidding game, each player may, after he examines his card drawn from the blind, bid on tricks; the pone having the first bid, the player to his left next and the dealer last. Thus the pone may first bid "three red", for instance, and the player to his left may next bid "four black", whereupon, if the dealer does not now over-bid the last bid, this particular game proceeds, with the black suit trumps, and with the player to the left of the pone under the obligation of taking at least four tricks. Scoring, as to the successful bidder and the other players, as affected by whether or not such bidder makes his bid or fails to do so, and in regard to tricks or honors or both, may be according to any schedule agreed—except that it is always desirable to have the cards carrying the higher numerical notations constitute the higher honors.

If it is a bidding game, the successful bidder leads first, the player to his left next, and the remaining player next.

In trick-taking power, the numerals at

the upper right-hand corners of the cards, are followed; the higher number having the greater power in the same suit, and a card of any numerical value of the trump suit or color having a greater power than any card of the other suit or color. The Joker is considered a pawn-card of the trump suit or color.

A deck of 32 cards as hereinabove described is preferred for a two-handed game, and such deck with the Joker or any other auxiliary card is preferred for a three-handed game; to have the same number of cards in each hand, and at the same time to utilize a number of cards of each suit or color corresponding to the number of different chessmen employed in the ordinary game of chess. Two colors or suits are preferred, rather than say a deck of 64 cards, having, for instance, red, orange, black and blue colors or suits, since there are only two colors or sets of chessmen in the ordinary game of chess.

It will be noted that the King card (Fig. 1) is, for example, given the numeral "10", that is, a value somewhat higher than that of the most powerful of the attacking chessmen (the Queen); in order to bring out, regardless of any differences of opinion as to the relative attacking power of the King when used occasionally as an attacker, the outstanding importance of the King in the ordinary game of chess, as it is of course generally known that check-mating an opponent's King wins the game.

Thus it will be seen that I have provided a novel and useful type of playing card, and deck of playing cards, and one well calculated to have all the advantages and attain all the objects hereinabove referred to.

Inasmuch as many changes could be made in the above-described embodiment, and many apparently widely different embodiments of the invention could be made without departing from the scope thereof, it is intended, as already pointed out in certain particulars, that all matter contained in the above description or shown in the accompanying drawing, shall be interpreted as illustrative and not in a limiting sense.

It is also to be understood that the language contained in the following claims is intended to cover all the generic and specific features of the invention herein described, as well also as all statements of the scope of the invention which, as a matter of language, might be said to fall therebetween.

I claim:

1. A deck of playing cards adapted to facilitate the learning of important features of the game of chess by the playing of a card game with said deck; said deck comprising thirty-two cards (for a two-handed game) and a joker which, when in play, makes a deck of thirty-three cards (for a three-

- handed game); the thirty-two cards first-mentioned being divided into two suits of sixteen cards each, each card of each suit bearing an indicium of the suit of which that card is a member, the indicia for the two suits being different, and in each suit the sixteen cards thereof being made up as follows, viz, one "King" card bearing thereon the conventional representation of a king, one "Queen" card bearing thereon the conventional representation of a queen, two "Castle" cards each bearing thereon the conventional representation of a castle, two "Knight" cards each bearing thereon the conventional representation of a knight, two "Bishop" cards each bearing thereon the conventional representation of a bishop, and eight "Pawn" cards each bearing thereon the conventional representation of a pawn; each of said King, Queen, Castle, Knight, Bishop and Pawn cards of both suits having a single numerical significance, such significance indicated on each card by an appropriate numerical, such numeral being "1" for a Pawn card, "2" for a Bishop card, "2" for a Knight card, "4" for a Castle card, "8" for a Queen card, and "10" for a King card.
2. The deck of playing cards as described in claim 1, wherein each Knight card, in addition to the numeral "2" carried thereby as aforesaid, also carries an indicium signifying that a Knight card is of higher value than a Bishop card.
35. ISADORE LAWRENCE LESAVOY.
